(57) **CLAIM**

The ornamental design for a mobile terminal case, as shown and described.

DESCRIPTION

FIG. 1 is a perspective view of a mobile terminal case; FIG. 2 is a front view of the mobile terminal case of FIG. 1; FIG. 3 is a rear view of the mobile terminal case of FIG. 1; FIG. 4 is a left-side view of the mobile terminal case of FIG. 1;

FIG. 5 is a right-side view of the mobile terminal case of FIG. 1;

FIG. 6 is a top plan view of the mobile terminal case of FIG. 1;

FIG. 7 is a bottom plan view of the mobile terminal case of FIG. 1;

FIG. 8 is a perspective view of the mobile terminal case of FIG. 1 illustrating an example of how the mobile terminal case may receive a mobile terminal, in which the evenly spaced broken line showing the mobile terminal is for illustrative purpose only and forms no part of the claimed design; FIG. 9 is a perspective view of the mobile terminal case of FIG. 1 in which the mobile terminal case is in its closed state; FIG. 10 is a side plan view of the mobile terminal case of FIG. 1 illustrating an example of how the mobile terminal case may be folded as a stand with a mobile terminal therein, in which the evenly spaced broken line showing the mobile terminal is for illustrative purpose only and forms no part of the claimed design; and,

FIG. 11 is a side plan view of the mobile terminal case of FIG. 1 illustrating another example of how the mobile terminal case may be folded as a stand with a mobile terminal therein, in which the evenly spaced broken line showing the mobile terminal is for illustrative purpose only and forms no part of the claimed design.
